LOCOMOTIVE FIREBOX

Gust J. Christenson, Chicago, Ill., assignor to
Locomotive Firebox Company, Chicago, Ill.,
a corporation of Delaware

Application June 13, 1936, Serial No. 85,064

8 Claims. (Cl. 122—68)

This invention relates to improvements in locomotive fireboxes and it consists of the matters hereinafter described and more particularly pointed out in the appended claims.

5 This invention is more particularly concerned with fireboxes equipped with a thermic siphon, of the type which is a substantially rigid water, steaming and circulating element that opens at its ends through certain sheets of the firebox at 10 different elevations, for the purpose of increasing the effective heating surface area of the firebox whereby a better water steaming and circulating action is possible.

One of the objects of the present invention is 15 to provide means in a siphon equipped firebox whereby additional water steaming and circulating efficiency and a better support for the arch brick is obtained.

Another object of the invention is to provide a 20 firebox of this kind, wherein water is taken from the front throat and at points along each side water leg and is discharged above the crown sheet at points therealong in a manner assuring a continuous flooding of the same with water, even 25 though the water level in the boiler falls below normal.

A further object of the invention is to provide 30 a tube arrangement in a locomotive type of firebox, which coacts with the siphon in forming a better support for the brick of the arch and at the same time employs longer tubes of a peculiar shape that gives them more flexibility to accommodate sheet movement.

The above mentioned objects of the invention 35 as well as others, together with the advantages thereof, will more fully appear as the specification proceeds.

In the drawing:

Fig. 1 is a longitudinal vertical sectional view 40 through a locomotive boiler embodying the preferred form of the invention.

Fig. 2 is a transverse vertical sectional view 45 through the same as taken on the line 2—2 of Fig. 1.

Fig. 3 is another and fragmentary transverse 50 vertical detail sectional view through a part of the firebox as taken on the line 3—3 of Fig. 1.

Referring now in detail to that embodiment of 55 the invention illustrated in the accompanying drawing, 5—5 indicate the side sheets of the firebox, and 6 indicates the crown sheet thereof. 7 indicates the front or flue sheet thereof and 8 indicates the back sheet thereof. It will be understood that the firebox is positioned in the rear 55 end of the boiler shell, which includes the outer

side sheets 9—9, top sheet 10, back sheet 11 and front throat sheet 12. Portions of the back sheets 8 and 11 respectively are formed to provide a fuel door opening 13.

Several of the sheets mentioned coact to form 5 the side water legs 14, back water leg 15 and front throat 16 respectively, all bottomed by a mud ring 17. The above is typical of a conventional locomotive boiler rear end structure and requires no further description except to say that companion sheets are suitably stay-bolted.

The firebox herein shown is equipped with a so-called thermic siphon 18 which is a substantially rigid but hollow water steaming and circulating element having ends that open through certain 15 sheets of the firebox at different elevations. When a plurality of such siphons are employed in the firebox, they are spaced laterally from each other.

In the present instance, only one siphon is employed 20 and this is disposed in the longitudinal median plane of the firebox. Such a siphon in this instance includes a substantially flat, triangularly shaped body 19 having an outwardly flared flange 20 at the top that fits and is welded 25 in a longitudinally extending elongated opening in the crown sheet. This body has an inclined bulged bottom 21 which extends downwardly and forwardly to terminate in a tubular inlet neck extension 22 that opens through the bottom portion 30 of the front sheet 7 so as to communicate with the front throat 16. The body which is closed at its front and rear ends is suitably staybolted 35 to resist internal pressures. It is apparent that the siphon presents a considerable surface area.

In the operation of the boiler in which the siphon 35 is installed, water is drawn in from the throat 16 and a part thereof is generated into steam, the steam and hot water being discharged into the boiler water and steam space of the boiler above 40 the crown sheet. In this discharge of water, the same operates to flood the crown sheet. By reason of the difference in thermic heads, a vigorous water circulating action is established in the boiler.

The siphon described, substantially divides the firebox longitudinally into two laterally spaced combustion chambers or passages both of which communicate with the flues of the boiler. In each chamber or passage is a set of circulator 50 tubes 23, each comprising a plurality of longitudinally spaced tube elements, the elements in one set on one side of the siphon being arranged in the transverse plane of the elements of the other set.

Each tube element includes an inlet portion 24, an outlet portion 25 and intermediate connecting portion 26 of reverse curve formation on the order of an ogee or bulge. The inlet portion has 5 an extremity 27 arranged at a right angle to the plane of the associated side sheet. This extremity which extends at a right angle to the plane of the side sheet is fixed in said side sheet and merges into the inlet portion 24 by a short 10 curved portion 28. The inlet portion 24 extends upwardly and inwardly from the curved portion 23 at an angle which corresponds to the angle of transverse inclination of one side of the arch which will be referred to later. The crown 15 sheet 6 is arched or curved transversely of the firebox and the outlet portion 25 of the tube extends radially with respect thereto and opens through and is fixed in any suitable manner in said crown sheet.

20 As herein shown, the intermediate portion 26 of each tube element 23 comprises upper and lower reversed curved parts and the lower part is so disposed as to be spaced substantially close to the associated side of the siphon body. The tube 25 elements in each set are of successively increasing heights, from the rear to the front of the firebox. This difference in heights is such that a line extending between the points where the inlet portions of the tube elements in each set, open 30 through the associated side sheet, is disposed in an inclined plane substantially conforming to the plane of inclination of the bulged bottom 22 of the siphon body and its neck extension.

The structure described is admirably adapted 35 to the support of an arch indicated as a whole as at 29 in Fig. 2. This arch is made of transverse rows of brick, each including an outer end brick 30, an inner end brick 31 and intermediate brick 32. The outer end and intermediate brick 40 30 and 32 are curved transversely of the plane of the respective row while the inner end brick is flat. The outer end and intermediate brick each has a concaved corner to rest upon upper parts of 45 the inlet portions of the tubes. The outer end of the outer brick in each row engages against the associated side sheet. The inner end of each inner end brick is cut away to permit it to pass the curved parts 26 of the tubes. Furthermore, the inner end of each inner end brick is formed 50 with a shoulder to engage upon the body bottom bulge 21 and inlet neck 22, respectively.

In the outer side sheets 9 of the boiler in line with the inlet end extremity 27 of the various tube elements, are wash-out plugs 33 and in the 55 top sheet 18 of the boiler shell are wash-out plugs 34 in line with the outlet ends of the various circulator tube elements 23.

In the operation of the boiler of which the firebox forms a part, the siphon operates to take 60 in boiler water from the front throat and to discharge it out through its top end, thus keeping the crown sheet flooded with water. Also, due to the presence of the sets or banks of circulator tubes, water enters the inlet ends of the various 65 tube elements at spaced points along each side water leg 14. Under the action of heat transfer from the products of combustion to the water in the tube elements 23, a part of the water is generated into steam to pass into the boiler above 70 the water therein and the remainder of said water is discharged out through the outlet ends to assist the siphon in keeping the crown sheet flooded to increase the safety factor under low water conditions.

75 As water is taken into the various tube ele-

ments 23 from longitudinal spaced points in each water leg, a continuous and vigorous circulation is established in the side water legs which washes the water side of the sheets clean of any solids tending to adhere thereto. Also due to the turbulence set up by the circulating action, the solids remain in suspension and cannot readily settle out to accumulate as a mud upon the mud ring which bottoms the various water legs.

By reason of the circulation thus produced 10 through the side water legs, the expansion and contraction stresses in the firebox sheets are equalized and the life of the same is greatly increased.

The tube elements 23 are preferably made of 15 seamless tubing and may be readily bent to shape. As the curves therein are of a relatively large radius, the danger of cracking in shaping the tubes is avoided. Also, such curves permit a ready wash-out of the tubes.

Cross reference is hereby made to applicant's 20 co-pending application S. N. 85,063 which claims certain of the subject matter herein disclosed, but not claimed herein.

While in describing the invention, I have referred in detail to the form, arrangement and construction of the parts thereof, this is to be considered only in the illustrative sense so that I do not wish to be limited thereto except as may be specifically set forth in the appended 30 claims.

I claim as my invention:

1. A locomotive firebox embodying therein a crown sheet, a front sheet and side sheets, a substantially rigid water steaming and circulating element in the firebox having ends which open through certain of the sheets of the firebox at different elevations, and a circulator tube arranged on each side of said element and extending transversely of the fire box, each tube including 35 an inlet portion opening through an associated side sheet and an outlet portion opening through the crown sheet and a reversely curved intermediate portion connecting said inlet and outlet portions, said reversely curved portions 40 being arranged relatively close to the sides of said element and being spaced closer together than the outlet portions of both tubes where they 45 open through the crown sheet.

2. A locomotive firebox embodying therein a 50 crown sheet, a front throat and side sheets, a substantially rigid water steaming and circulating element in the median plane of the firebox having ends which open through certain of the sheets of the firebox at different elevations, sets of circulator tubes in and arranged transversely of the firebox, with one set arranged on each side of the water steaming and circulating element and each set comprising a plurality of tube elements arranged in transverse planes, spaced longitudinally of the firebox, each tube comprising an inlet portion opening through an associated side sheet and an outlet portion opening through the crown sheet and a reversely curved intermediate portion connecting said inlet and outlet 60 portions, the reversely curved portions of the tubes in each set being arranged substantially close to the sides of said element, said last mentioned portions of the tubes in both sets being spaced closer together than the outlet portions 65 of the tubes in both sets where they open through the crown sheet.

3. A locomotive firebox embodying therein a crown sheet, a front sheet and side sheets, a substantially rigid water steaming and circulat- 75

- ing element in the median plane of the firebox having ends which open through certain of the sheets of the firebox at different elevations, sets of circulator tubes in the firebox, with one set 5 arranged on each side of the water steaming and circulating element and each set comprising a plurality of tube elements arranged in transverse planes spaced longitudinally of the firebox, each tube comprising an inlet portion opening through 10 an associated side sheet and an outlet portion opening through the crown sheet and a curved intermediate portion connecting said inlet and outlet portions, and a fire arch composed of brick supported in part by said water steaming 15 and circulating element and in part by said circulator tubes.
4. A locomotive firebox embodying therein a crown sheet, a front sheet and side sheets, a substantially rigid water steaming and circulating 20 element in the median plane of the firebox having ends which open through certain of the sheets of the firebox at different elevations, sets of circulator tubes in the firebox, with one set arranged on each side of the water steaming and 25 circulating element and each set comprising a plurality of tube elements arranged in transverse planes spaced longitudinally of the firebox, each tube comprising an inlet portion opening through an associated side sheet and an outlet portion 30 opening through the crown sheet and a curved intermediate portion connecting said inlet and outlet portions, and transverse rows of fire brick between and supported at least in part on the inlet portions of adjacent tube elements in each 35 set and closing the space between the sides of said water steaming and circulating element and the respective side sheets.
5. A locomotive firebox embodying therein a crown sheet, a front sheet and side sheets, a substantially rigid water steaming and circulating 40 element arranged longitudinally of the firebox and having ends which open through certain of the sheets of the firebox at different elevations, a set of circulator tubes arranged in and extending transversely of the firebox on each side of the 45 water steaming and circulating element, each set of tubes comprising a plurality of tube elements arranged in transverse planes spaced longitudinally of the firebox, each tube comprising an inlet portion opening through the side 50 sheets, an outlet portion opening through the crown sheet and a reversely curved intermediate portion connecting said inlet and outlet portions, and means providing arch portions between both 55 sides of said element and said side sheets, said arch portions comprising bricks, certain ones of which are supported solely upon said inlet portions of said tubes and others of which are supported jointly upon said inlet portions and upon 60 portions of said element.
6. A locomotive firebox embodying therein a crown sheet, a front sheet and side sheets, a water steaming and circulating element in the firebox and including a flat hollow body arranged longitudinally of the firebox and opening through the 65 crown sheet, said body having a downwardly and forwardly inclined bulged bottom that merges into a tubular neck which opens through the throat sheet of the firebox, a set of circulator tubes arranged in and extending transversely of the firebox on each side of the water steaming and circulating element, each set comprising a plurality of tube elements arranged in transverse planes spaced longitudinally of the 70 firebox, each tube including an inlet portion, the inlet portions of all the tubes in each set opening through the associated side sheet in a plane substantially corresponding to the plane of the inclination of the bottom of the said body and its neck extension, each tube further including an outlet portion opening through the crown sheet and a reversely curved intermediate portion connecting said inlet and outlet portions, and transverse rows of fire brick between the inlet portions of adjacent tube elements and extending from said body 75 to the respective side sheets.

GUST J. CHRISTENSON.
